R. F. STEHLIK

AUTOMATIC TELEPHONE SYSTEM

Filed March 19, 1923

Patented Sept. 21, 1926.

UNITED STATES PATENT OFFICE.

RUDOLPH F. STEHLIK, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

AUTOMATIC TELEPHONE SYSTEM.

Application filed March 19, 1923. Serial No. 625,997.

The present invention relates to automatic telephone systems in general, but is more particularly concerned with automatic telephone systems in which finder switches are employed; and the principal object, briefly stated, is the production of a finder system which is reliable in operation and which uses switches which are simple in construction.

More specifically, an object of the invention is the production of a finder switch system using a finder switch of which the start and test or switching relays are replaced by a single relay that does the work of both.

Another object is the provision of a simple and effective arrangement for restarting a finder in case it stops on the terminals of a non-calling line due to the accidental removal of ground from the test contact thereof.

Still another object is to provide suitable circuit arrangements for causing a second finder to find a calling line in case the first to find such line is unable to establish a holding circuit for itself.

Such other features as are not mentioned here will appear fully and be described during the course of this specification.

Referring now to the accompanying drawing, there is shown by means of the usual circuit diagrams a sufficient amount of apparatus in a telephone system embodying the principles of the invention to enable the invention to be understood.

A telephone line is shown extending from the substation A to the exchange where it terminates in the banks of a group of finder switches such as the finder F, and has associated with it the line circuit LC. This drawing shows also the finder allotter FA,

which extends the starting circuit to an idle finder after the allotted one is taken for use. The drawings show also the selector E which is linked with the finder F by the conductors 75-77, inclusive.

The substation A is an automatic substation, and is, therefore, provided with a calling device in addition to the other usual and well known instrumentalities.

Each of the finders such as the finder F, together with the finder allotter FA, is mechanically of the well known rotary type of switch in which the wipers have no normal position and are advanced in a forward direction only by the stepping magnet, and in which the wipers are advanced when the

stepping magnet deenergizes rather than when the stepping magnet energizes.

The selector E is an automatic switch of the usual vertical and rotary type of which the bank contacts are arranged in horizontal rows or levels.

In order to explain the detailed operation of the equipment shown, it will be assumed that the subscriber at substation A desires to make a call and, accordingly, removes his receiver from the switch-hook.

When the receiver is removed at substation A, a circuit is closed over line conductors 11 and 12 for the upper winding of the combined line and cut-off relay 14. Owing to the resistance 15, which is included in this circuit, the relay 14 energizes only sufficiently to operate the armatures 17 and 19.

Armature 17, upon being attracted, disconnects test contact 22 from ground and connects it to the private normal conductor 13, and armature 19, upon being attracted, places ground on start wire 29, thereby closing a circuit for the lower winding of the combined start and test or switching relay 63 of the finder F as follows: From ground by way of armature 18 of relay 14 and its resting contact, working contact of armature 19 and said armature, start conductor 29, series signal relay 31, armature 42 and its resting contact, wiper 46, conductor 50, resting contact of armature 72 and said armature, and the lower winding of the marginally adjusted relay 63 to battery. Relays 63 and 31 energize in series over this circuit, and relay 31 opens a point in the circuit of the common alarm buzzer 35 to prevent said buzzer from operating in response to the energization of relay 30 which occurs at this time.

Owing to the fact that the current through the lower winding of relay 63 is limited by the high resistance series relay 31 in the finder allotter FA, relay 63 energizes only sufficiently to operate armatures 70 and 71. Armature 71, upon being attracted, closes a circuit for the upper winding of relay 63 in series with stepping magnet 61 as follows: From ground by way of wiper 44 of the allotter FA, conductor 48, armature 71 and its working contact, upper winding of relay 63, interrupter contacts 64 and stepping magnet 61 to battery. Armature 70, upon being attracted, connects test wiper 25 to the junction of the upper or test winding of re-

lay 63 and stepping magnet 61. The further operation of the finder F depends upon whether the wipers 24-26, inclusive, of the finder F are standing upon a calling or non-calling line. In case the wipers of the finder are standing upon the terminals of a calling line, test wiper 25 is in engagement with an ungrounded test contact and the operation of armature 70 is without effect, and the upper winding of switching relay 63 becomes energized immediately with the result that the remaining armatures of the relay are fully operated.

In the present case, however, it will be assumed that the terminals upon which the wipers of the finder are standing are the terminals of a non-calling line. In this case, the terminal engaged by test wiper 25 is grounded through an armature and its resting contact corresponding to armature 17 and its resting contact. That being the case, the upper winding of relay 63 is short circuited and does not become energized. In this case, the ground potential encountered by test wiper 25 is extended through armature 70 and its working contact, and interrupter contacts 64 to stepping magnet 61. By the operation of stepping magnet 61 over this circuit, the wipers 24-26, inclusive, are rotated step by step owing to the buzzer-like action of said magnet 61 occasioned by the interrupter contacts 64.

When the wipers 24-26, inclusive, of the finder F arrive upon the terminals 21-25, inclusive, of the calling line, test wiper 25 engages the ungrounded test contact 22 and the stepping movement of the finder accordingly ceases. When this occurs, the previously traced circuit through the upper winding of relay 63 becomes effective, whereupon relay 63 energizes fully, thereby attracting the remaining armatures. Upon the complete energization of relay 63, the line conductors are connected through at armatures 68 and 74; a local circuit is closed for stepping magnet 61 at armature 73; the lower winding of relay 63 is shifted from start conductor 50 to the release trunk conductor 76 at armature 72; and at armature 69 test wiper 25 is disconnected from the junction of the upper winding of relay 63 and stepping magnet 61, and connected to the upper winding of the special test relay 62 by way of armature 65 and its resting contact. The armature of relay 62 is lightly adjusted, and this relay accordingly energizes quickly in series with the lower or cut-off winding of relay 14 over the following circuit: From ground by way of the upper winding of relay 62, resting contact of armature 65 and said armature, working contact of armature 69 and said armature, test wiper 25, test contact 22, armature 17 and its working contact, and the lower winding of relay 14 to battery. Upon energizing over the above

traced circuit, relay 62 closes a locking circuit for its lower winding at armature 66, which includes the working contact of armature 73 and said armature, and at armature 67 opens the circuit of stepping magnet 61 before said stepping magnet has had time to energize, and closes a circuit for relay 32 of the finder allotter FA, which will be described later. It may be pointed out that, whereas the stepping magnet 61 has a comparatively heavy armature and a stiff adjustment, the relay 62 has a lighter armature and a less stiff adjustment, and for that reason is able to energize and open the circuit of stepping magnet 61, as above pointed out, before stepping magnet 61 can operate. The above mentioned circuit for relay 32 of the finder allotter FA is as follows: From ground by way of the working contact of armature 73 and said armature, armature 67 and its working contact, conductor 49, wiper 45, armature 41 and its resting contact, and relay 32 to battery. Relay 32 does not energize immediately upon the closure of this circuit owing to the fact that its core has a copper collar placed on the armature end thereof as is indicated by the black upper portion of the core.

As a further result of the energization of the special test relay 62, test wiper 25 is disconnected from the upper winding of relay 62 (leaving relay 62 locked up over its lower winding) and extended to release trunk conductor 76.

As a result of the line conductors of the calling line being connected up at armatures 68 and 74 of relay 63, as pointed out above, line relay 135 of the selector E energizes over the calling subscriber's line and closes a circuit for release relay 136 at armature 151. Release relay 136, upon energizing, opens a point in the circuit of release magnet 144 and prepares a circuit for vertical magnet 140 at armature 153, and at armature 152 applies ground to the release trunk conductor 76. This ground potential extends by way of the working contact of armature 72 and said armature to the lower winding of relay 63, thereby completing a holding circuit for this relay. The ground potential applied to release trunk conductor 76 extends also by way of the working contact of armature 65 and said armature, and thence by way of the previously traced circuit to battery through the lower winding of relay 14. Relay 14 now energizes sufficiently to attract the remaining armatures, thereby disconnecting ground from start conductor 29 at armature 18 and removing the bridge from across the calling line at armatures 16 and 20. A branch of the circuit of the lower winding of relay 14 extends by way of the private normal conductor 13 to multiply connected test contacts in the banks of the connector switches having 136

access to the line of substation A, thereby guarding said line against intrusion in the usual manner.

As a further result of the ground potential being applied to release trunk conductor 56 of the selector E, a circuit is closed for the upper winding of relay 33 of the finder allotter FA through conductor 47 and test wiper 43. Relay 33, upon energizing, opens the circuit of relay 32 at armature 41 before said relay 32 has had time to energize, and at armature 42 opens the starting circuit so as to prevent interference with the finders passed over by the wiper 46, which is subsequently rotated. A branch of the circuit of the upper winding of relay 33 extends by way of interrupter contacts 40 to stepping magnet 34, and accordingly the stepping magnet 34 is operated in the manner of a 10 buzzer with the result that the wipers 43-46, inclusive, are operated step by step in search of an idle finder. The wipers of the finder allotter stop upon the next idle finder being reached owing to the absence of a ground 15 potential on the test contact thereof, and relay 33 accordingly deenergizes.

It will be noted that wiper 44, on moving off the bank contact 48, opens the circuit of the upper winding of the two-step relay 63. This leaves relay 63 locked up by means of its lower winding which is energized from the release trunk conductor 76 through the working contact of armature 72 and said armature. This winding, although unable 20 to energize the relay sufficiently to operate all the armatures when its circuit is closed through the high resistance series relay 31 of the finder allotter FA, is now energized through a circuit which does not include the high resistance relay 31 and for that reason 25 easily maintains the relay operated just like any ordinary relay winding.

When the calling subscriber operates his calling device in accordance with the first 30 digit in the desired number, the circuit of line relay 135 (switch E) is opened a corresponding number of times. Each time line relay 135 deenergizes in response to one of the interruptions thereby produced, it closes a circuit for vertical magnet 140 as follows: From ground by way of the resting contact 35 of armature 159 and said armature, armature 151 and its resting contact, armature 153 and its working contact, relay 137, and vertical magnet 140 to battery. By the operation of vertical magnet 140, the wipers 161-163, inclusive, are raised opposite the desired level of bank contacts. Relay 137 is energized in series with vertical magnet 140 40 and, being slow-acting, retains its armature attracted throughout the vertical movement.

As a result of the energization of relay 137, it closes a circuit at armature 154 for stepping relay 138 by way of off normal contacts 45 143 (which close upon the first vertical step)

and interrupter contacts 142. Stepping relay 138, upon energizing, closes a locking circuit for itself at armature 155, and at armature 156 prepares a circuit for rotary magnet 141.

At the end of the vertical movement, slow-acting relay 137 deenergizes and completes the circuit of rotary magnet 141 at armature 154. Rotary magnet 141, upon energizing, advances the wipers 161-163, inclusive, into engagement with the first set of bank contacts in the selected level, and, near the end of its stroke, opens the circuit of stepping relay 138 at interrupter contacts 142. Stepping relay 138, upon deenergizing, opens the circuit of rotary magnet 141 at armature 156, whereupon rotary magnet 141 deenergizes also and closes its interrupter contacts 142 again. In case the trunk terminating in the first set of bank contacts is idle, switching relay 139 energizes immediately. Assuming the trunk to be busy, however, switching relay 139 is short-circuited by the ground potential encountered by test wiper 162, and stepping relay 138 energizes from this same ground potential and closes the circuit of rotary magnet 141 again, whereupon the switch wipers are rotated into engagement with the next set of bank contacts. This alternate operation of stepping relay 138 and rotary magnet 141 continues until an idle trunk is reached, which trunk it will be assumed is the one terminating in bank contacts 164-166, inclusive, whereupon switching relay 139, being no longer short-circuited, energizes in series with stepping relay 138. Stepping relay 138, however, does not energize at this time on account of the high resistance of switching relay 139. Switching relay 139, upon energizing, opens a point in the test circuit and prepares the holding circuit at armature 158; disconnects ground from armature 151 of line relay 135 at armature 159, thereby opening the circuit of release relay 136; and at armatures 157 and 160 disconnects conductors 75 and 77 from the windings of line relay 135, and extends them by way of wipers 161 and 163 and bank contacts 164 and 166 to the windings of the line relay (not shown) of the switch to which the seized trunk extends. Holding ground is now supplied by way of the release trunk conductor of the seized switch through test contact 165, test wiper 162, and armature 158 and its working contact to release trunk conductor 76. This ground potential is supplied prior to the deenergization of the slow-acting release relay 136 and serves to maintain the operated switches in their respective operated positions.

The calling subscriber now dials the remaining digits in the desired number with the result that the connection is completed 130 in the well-known manner and, when he

replaces his receiver, after having either completed the desired connection or abandoned the call, the ground potential is removed from the release trunk conductor 76

5 by the switch to which the connection has been extended and relays 14, 63, and 139 accordingly deenergize. The deenergization of switching relay 139 of the selector E results in the circuit of release magnet 144

10 being closed at armature 159, whereupon the said release magnet 144 energizes and the switch wipers are restored to normal position in the usual manner, whereupon the circuit of release magnet 144 is opened at the

15 off normal contacts 145.

The deenergization of the combined line and cut-off relay 14 of the calling line restores the associated circuits to normal, and the deenergization of the relay 63 of the

20 finder F results in the associated circuits being restored to their normal condition, and the circuit of the lower winding of relay 62 is opened at armature 73, whereupon relay 62 deenergizes. The entire connection

25 is now released and the apparatus involved is in readiness to be used in a subsequent call.

In order to explain how a finder switch such as the finder F, for example, is re-started after having stopped on a non-calling line, it will be assumed that the start wire 29 is grounded due to some line other than the line of substation A calling. It will be assumed further that the finder allotter is in the position shown in the drawing and, consequently, that the finder F is

30 started in search of the calling line. A still further assumption that will be made at this time is that the wipers 24-26, inclusive, of the finder F reach the terminals of the line of substation A before they reach the terminals of the calling line and that armature 17 of relay 14 is either not properly ad-

35 justed or else the resting contact thereof is covered with dust or some other insulating material. That being the case, the test contact 22 is ungrounded and the finder F ac-

40 cordingly stops on the terminals 21-23, inclusive, and the two-step relay 63 energizes completely. In this case, since armature 17 of relay 14 is not attracted, the lower wind-

45 ing of relay 14 is not connected up and no circuit is closed for the upper winding of the special test relay 62. Under these con-

50 ditions the test relay 62 remains deenergized and the circuit of stepping magnet 61 through the working contact of armature 73, armature 67 and its resting contact, and the resistance 64 remains closed sufficiently

55 long to permit stepping magnet 61 to energize. Upon energizing, stepping magnet 61 opens its interrupter contacts in the usual manner, with the result that the circuit of the upper winding of relay 63 is opened and

60 said relay 63 deenergizes and opens the circuit of stepping magnet 61 at armature 73,

whereupon stepping magnet 61 deenergizes also. Due to the energization and deenergization of stepping magnet 61, the switch wipers 24-26, inclusive, are stepped to the next set of contacts and, upon relay 63 again energizing part way over its lower winding, the finder F starts operating again, with the result that the calling line is found in the usual manner.

It has been described hereinbefore how the finder allotter FA is caused to allot the next finder in response to the grounding of the release trunk conductor 76 of the finder F by the release relay 136 of the selector E. It may happen at rare intervals that one of

30 the three conductors of the trunk extending between the finder F and the selector E may be open, with the result either that the line relay 135 does not energize or that the energization of line relay 135 is ineffective

35 to cause the release trunk conductor 76 to be grounded. In this case the usual circuit for stepping magnet 34 is not closed through wiper 43 and the slow to energize relay 32

40 is able to energize over its previously traced circuit which includes the attracted armatures 73 and 67 and armature 41 and its resting contact. Upon energizing, relay 32

45 closes a circuit for stepping magnet 34 at armature 38, whereupon stepping magnet 34 energizes and moves the associated pawl into engagement with the next notch in the wiper driving ratchet wheel, but owing to the fact that its wipers are advanced upon the deenergization rather than its energiza-

50 tion, it does not move the associated wipers. As a further result of the energization of relay 32, it closes a circuit for relay 33 at armature 39, whereupon relay 33 energizes

55 and opens the circuit of relay 32 at armature 41, whereupon relay 32 deenergizes and opens the circuit of stepping magnet 34,

60 with the result that stepping magnet 34 deenergizes and advances the wipers 43-46, inclusive, into engagement with the terminals of the next finder.

In the finder F, relay 63 deenergizes in response to the wiper 44 moving off bank contact 48, owing to the fact that no holding circuit for the lower winding has been closed over release trunk conductor 76. This results in the conditions in the finder F being restored to normal.

Since the start conductor 29 is still grounded owing to the fact that the two-step relay 14 has not been operated fully, the next allotted finder is immediately started in search of the calling line.

It occasionally happens that the starting circuit is open at some point between the high resistance series relay 31 and the start winding of the allotted finder and, when such a condition exists, it is desired that the attendant be notified. When the starting circuit is open at one of the above men-

125
130
135

tioned points, the result is that, while relay 30 energizes in the usual manner owing to the fact that the start conductor 29 is grounded, the series relays 31 is unable to energize and a circuit is closed for the common alarm buzzer 35 through the resting contact of armature 37 and said armature and armature 36 and its working contact. This operation notifies the attendant who may take such steps as he deems necessary to clear up the trouble.

What is claimed is:

1. In a telephone system, lines, a finder switch for extending said lines when calling, a starting circuit, means individual to the line calling which directly closes said starting circuit responsive to a call, a marginal relay associated with said finder responsive to the closure of said starting circuit for operating said relay part way to start said finder in search of the calling line, and means for operating said relay still further to complete the connection to the calling line when the same is found.
2. In a telephone system, subscribers' lines, a trunk line, a finder switch for extending a calling one of said lines to said trunk line, a combined starting and switching relay in said finder having two windings, a circuit controlled by the calling subscriber for partially operating said relay by energizing one winding to cause it to perform its starting function, and another circuit extending through the other winding completed when the calling line is found for fully operating said relay to cause it to perform its switching function.
3. In a telephone system, subscribers' lines, a trunk line, a finder switch for extending a calling one of said lines to said trunk line, a combined starting and switching relay in said finder, a circuit controlled over the calling line for partially operating said relay, circuits completed by said relay when partially operated for causing said finder to hunt for and stop on the calling line, a circuit for fully operating said relay to stop the finder, and contacts closed by said relay only when fully operated for connecting the calling line with said trunk line.
4. In a telephone system, lines, a test contact for each line, said test contacts having a normal test potential, a finder switch having a test wiper for making connection successively with said test contacts, means for removing said normal test potential from the test contact of a calling line and for starting said finder in search of said calling line, means for continuing the movement of said finder switch only so long as said test wiper engages test contacts which are at said normal potential, a test relay, means for closing a circuit for restarting said finder and for connecting said test relay to said test wiper when the latter reaches any test con-

tact not at said normal potential, and a circuit including said test wiper for operating said test relay to open said restarting circuit in case the test contact engaged by said test wiper is that of the calling line.

70

5. In a telephone system, a plurality of link circuits, an allotter for allotting another idle one of said link circuits when the last allotted one is taken for use, means in an allotted link circuit for starting said allotter in search of another idle link circuit when the allotted link circuit is taken for use, and slow-acting means controlled from the allotted link circuit for starting said allotter after an interval in case the first mentioned starting means is ineffective.

75

6. In a telephone system, a group of subscribers' lines, a group of trunk lines, a group of finder switches for extending calling subscribers' lines to idle trunk lines, there being a finder for each trunk line, an allotter for starting said finders successively responsive to successive calls from said subscribers' lines, and means for automatically releasing an operated finder and for starting another finder in case any conductor of the trunk line associated with the operated finder is open.

80

7. In a telephone system, a group of subscribers' lines, a group of trunk lines, a group of finder switches for extending calling subscribers' lines to idle trunk lines, there being a finder for each trunk line, a starting circuit, an allotter for maintaining said circuit in association with a selected idle finder, means controlled over a calling line for closing said starting circuit to start the selected finder, means controlled over the trunk line associated with such finder for advancing the allotter to shift the starting circuit when the finder locates the calling line, and additional means effective in case the trunk line is open for releasing the operated finder and for advancing the allotter to select another finder.

100

8. In a telephone system, automatic finder switches, a starting circuit therefor, a relay bridged across and a relay in series with said starting circuit, a signal, means for closing said starting circuit at one point, and means controlled jointly by said relays for operating said signal in case said starting circuit is open at another point.

115

9. In a telephone system, a finder switch, a starting relay in said switch, a starting circuit having two branches, the first branch extending to said relay, a second relay in which the second branch terminates, a third relay in series with the first branch, means for closing said circuit to energize said relays, and a signalling circuit including normally open contacts on said second relay and normally closed contacts on said third relay.

120

10. In a telephone system, a finder switch, a test contact for each line, said test contacts having a normal test potential, a finder switch having a test wiper for making connection successively with said test contacts, means for removing said normal test potential from the test contact of a calling line and for starting said finder in search of said calling line, means for continuing the movement of said finder switch only so long as said test wiper reaches any test contact not at said normal potential, a test relay, means for closing a circuit for restarting said finder and for connecting said test relay to said test wiper when the latter reaches any test contact not at said normal potential.

125

130

- a relay in said finder having contact springs and an armature for actuating them, means responsive to a call for causing said relay to partially operate its armature to close an operating circuit through certain of said springs, and means for causing said relay to fully operate its armature when the calling line is found to stop the finder and complete the connection to such calling line through 10 certain other of said springs.
11. In a finder switch, a combined start, stop and switching relay having only two stages of operation, an operating circuit closed only in the first stage, and talking conductors closed only in the second stage.
12. In a finder switch, a relay having a core and armature, contact springs directly actuated by said armature, means for operating said armature part way to close an operating circuit for the finder through certain of said springs, and means for fully operating said armature to open said operating circuit at certain other of said springs.
13. In a finder switch, a marginal two step relay, and an operating circuit for said finder completed on the first step and only opened on the second.
14. In a finder switch having wipers, a double wound relay, a starting circuit including one winding of said relay, and a test circuit including the other winding and a wiper of the switch.
15. In a telephone system, a finder switch, means for starting said switch in search of a calling line, a relay energized when the finder is stopped, whether the calling line has been reached or not, a restarting circuit closed by said relay, a test relay for testing the line on which the finder has stopped, and means controlled by said test relay for opening said restarting circuit if the line tested is the calling line.
16. In a telephone system, a finder switch, means for starting said switch in search of a calling line, a relay energized when the finder is stopped, whether the calling line has been reached or not, a restarting circuit closed by said relay, a test circuit also closed by said relay, a relay in said test circuit for testing the line on which the finder has stopped, said test relay being energized if the finder has stopped on the calling line, and means controlled by said test relay for opening said restarting circuit.
17. In a telephone system, a group of finders, an allotter having a plurality of wipers for selecting idle finders, a magnet, two circuits for operating said magnet to advance said allotter, each circuit including a wiper of the said allotter, and means for rendering one circuit effective only when the other is ineffective.
18. In a telephone system, a group of finders, an allotter for pre-selecting an idle finder, a circuit for starting the pre-selected
- finder responsive to a call, means responsive to the completion of the connection with the calling line for advancing said allotter to select another finder, and other means for causing the advance of said allotter responsive in case the first means fails.
19. In a telephone system, a group of finders, an allotter for pre-selecting an idle finder, a circuit for starting the pre-selected finder responsive to a call, means responsive to the completion of the connection with the calling line for advancing said allotter to select another finder, and other means for causing the advance of said allotter effective only in case the said first means fails to accomplish the advance of the allotter within a pre-determined time.
20. In a telephone system, a finder switch, a starting circuit having two branches, one branch including a start relay for said finder, a second relay included in said first branch in series with said start relay, a third relay included in the second branch, and a signal controlled jointly by said second and third relays.
21. In a telephone system, a finder switch, a start relay and circuit therefor, a signal and a circuit therefor, means for closing both circuits, and means controlled over the start circuit for opening the signalling circuit.
22. In a telephone system, a finder switch, a start relay and circuit therefor, a signal and a circuit therefor, means for closing the start circuit, means responsive to such closure for closing the signalling circuit, and means responsive only in case the start circuit is intact throughout for opening the signalling circuit.
23. In a telephone system, lines, a finder switch for extending connections to any calling one of said lines, a combined start and switching relay in said finder responsive to the initiation of a call, to start the same to hunt for a calling line, a circuit for further operating said relay also completed by it when operated to start the finder, and a source of current preventing the last circuit being effective until the finder connects with the calling line.
24. In a telephone system, subscribers' lines, a trunk line, a finder switch for extending a calling one of said lines to said trunk line, a combined starting and stopping relay in said finder, a circuit controlled by the calling subscriber for partially operating said relay to cause it to perform its starting function, and another circuit completed when the calling line is found for fully operating said relay to cause it to perform its stopping function.
- In witness whereof, I hereunto subscribe my name this 15th day of March, A. D., 1923.

RUDOLPH F. STEHLIK.
